UNITED STATES PATENT OFFICE.

JACOB GERRITSON AND WILLIAM L. RIECK, OF KANKAKEE, ILLINOIS.

BULKHEAD STRUCTURE.

1,350,603.

Specification of Letters Patent. Patented Aug. 24, 1920.

Application filed December 6, 1919. Serial No. 343,059.

To all whom it may concern:

Be it known that we, JACOB GERRITSON and WILLIAM L. RIECK, citizens of the United States, residing at Kankakee, in the 5 county of Kankakee and State of Illinois, have invented certain new and useful Improvements in Bulkhead Structures, of which the following is a specification, reference being had therein to the accompanying 10 drawing.

This invention relates primarily to bulkhead structures, and has more especial reference to a cement-stop which is juxtaposed to one face of the bulkhead.

15 The object of the invention is to provide a simple, but effective, expedient for covering the notches or incuts in the lower edge of a bulkhead that is utilized in pouring or otherwise forming a floor-slab. In the 20 usual practice, a wooden bulkhead is disposed upon a floor-support or the like, this bulkhead being provided with a series of notches or incuts at its lower edge through which project the reinforcing bars, rods or 25 wires that are eventually embedded in the cement. These notches are necessarily of considerably larger dimensions than the diametral dimensions of the rods, in consequence of which a space of some area is 30 formed around the reinforcement rods; and, through such spaces the poured concrete oozes into the space where the next floor-slab is to be poured. In consequence, a considerable amount of cement, of the rich- 35 est and most desirable part of the mix, is wasted; and, moreover, by reason of the fact that this cement which oozes through these spaces sets, it is difficult to remove it; and, besides, the portion of the slab at this 40 point is much weaker and, when the bulkhead is removed, the concrete discloses a honey-comb effect. Still, again, if the concrete which works through the bulkhead is not thoroughly removed, there is danger 45 that the next slab that is poured will be weaker because of the fact that the cement dries and sets and will not properly bond with the freshly-poured slab.

The device which we propose is designed 50 to preclude the objections pointed out; and, to this end, in addition to providing a bulkhead of considerable strength and rigidity, we combine therewith a series of notch-covering stops for preventing the cement from 55 running through the notches, these stops being readily located in juxtaposition to the

rod-receiving notches in the bulkhead preliminary to the pouring of the cementitious mass.

With this and other objects in view, the 60 invention resides in the construction, in the aggroupment of certain components which constitute this construction, and in certain essential details thereof, all as will more 65 fully hereinafter appear.

In order that the invention may more readily be comprehended, we have revealed the same in the accompanying drawings, these being, however, merely illustrative of a preferred and practical embodiment of the 70 invention; and we desire it to be understood that the invention is susceptible of a wide range of variation and modification from the illustrated embodiment without departing from the spirit of the invention or sacrificing any of its salient features or underlying principles.

In these drawings:

Figure 1 is a fragmentary view in perspective of the components required for 80 forming a concrete slab, together with a preferred form of our invention aggrouped therewith;

Fig. 2 is a view in front-elevation of the cement-stop in the form in which we prefer 85 to make it;

Fig. 3 is a similar view of a modified form of stop;

Fig. 4 is a fragmentary view in sectional-elevation showing the stop in position to 90 cover a bulkhead notch and with a mass of cement formed against the same;

Fig. 5 is a similar view, but with a portion of the cement broken away to more clearly show the stop in contact with a bulkhead;

Fig. 6 is a fragmentary view in vertical-section showing a bulkhead with our improved stop juxtaposed thereto and with a mass of cement set against the bulkhead and 100 the stop and embedded reinforcing wires; and

Fig. 7 is a view similar to Fig. 6, but with our stop omitted and, thus, disclosing the effect of the cement oozing through the bulkhead notch.

Referring to these drawings, it will be observed that the reference-numeral 1 designates, generally, a floor of slab-forming boards sustained by beams or supports 2 for 110 the falsework construction.

Upstanding from the floor 1 is a bulkhead

designated, generally, 3 and comprising uprights 4 and boards 5, 6 and 7. The uprights are held rigid by an angular brace 8 comprising a bulkhead-cleat 4, a bulkhead-block 8^b and a bulkhead brace-member 8^c, respectively, secured to the floor 1 and also to the uprights.

The base of the bulkhead, and particularly the part thereof formed by the board 7, is 10 provided with a plurality of incuts or notches 9 which are, preferably and as shown, rectangular in form. Extending through these notches are a series of reinforcing bars, wires or rods 10; and in conjunction with these is a series of transverse reinforcing bars, wires or rods 11.

It has been the usual practice, heretofore, to pour the cement onto the support, like the floor 1, and against a bulkhead of a type 20 somewhat like that herein marked 3. When this was done, a portion of the cement flowed or oozed through the openings 9 and onto a portion of the floor to the rear of the bulkhead, as at 12 in Fig. 7. We have found that 25 it is essential, for reasons already herein-before specified, and it is important—in fact, rather essential practice—to provide means for covering the openings 9 so as to block the flow of the cementitious mass, as in the 30 manner illustrated in Fig. 6. To this end, we have designed a stop herein designated, generally, by the reference-numeral 13. This comprises a member, preferably square in form, relatively thin in cross-section, and desirably made of a flexible material such as 35 paper or the like, which has no characteristic of undesirably affecting the cement while setting or hardening and thereby effecting a cracking of the same or otherwise 40 undesirably affecting it. These stops 13 must be capable of being located in juxtaposition to the openings 9 after the rods or wires have been projected therethrough; and it is 45 regarded as important to have these stops firmly embrace the rods 10, first in order 50 that they, themselves, may be held in proper relation to the bulkhead and to the floor 1 while the cement or concrete is being poured and while setting; and, also, in order to aid 55 in the support of the rods 10 in relation to the floor 1. To this end, the members 13 are provided with an aperture 14. In the 60 type of stop shown in Figs. 1, 2, 5 and 6, the aperture 14 is formed by providing the 65 central portion of the member with a series of radiating slits or cuts 15 and by bending or otherwise forming the points 16 outwardly, the formation thus produced resulting in a counter-sink or depression 17. Ex- 70 tending from one edge of the member 13 to the aperture 14 is a slit or cut 18, and, in this instance, it preferably constitutes an extension of one of the slits 15.

The member 13 is, preferably and as 75 shown, divided into a body-portion 19 and

into a base-portion 20, the latter being formed by perforating or scarifying the lower section of the member, as at 21 and 22, so that the portion 20 may be bent at right angles to the plane of the body portion 19 and thereby provide a base-portion 20, as shown in Figs. 1, 4, 5 and 6, and which base-portion engages the upper surface of the floor 1 at right angles to the face of the bulkhead 3.

The purpose of providing the stop with a slit 18 is to permit the same to be positioned about the reinforcing rod or bar 10; and, to that end, the stop is, as already stated, made of flexible material in order that it may be 80 placed in position, the slit 18 permitting the two proximate sections 24 and 25, at opposite sides of the slit 18, to be bent away from each other temporarily. Another feature which characterizes the provision of the slits 85 14 is that the points formed by these radiating slits—when the reinforcing rod extends through the aperture—are caused to project outwardly and away from the face of the bulkhead so that, when the concrete is poured 90 against the stop, the weight and pressure of the cement will tend to tighten and push the points more tightly against the rod.

The slits 15 permit this movement of the 95 sections 24 and 25 without tearing or injuring the portions of the member about the central aperture 14.

In Fig. 3, a modified form of stop is shown. In this instance, the stop-member 26 is provided with a slit or cut 27 extending 100 from one edge thereof to a central aperture 28 of approximately the same diameter as that of the reinforcing bar, rod or wire which is to be positioned therein. To provide against the tearing of the member while 105 the rod is being placed in position in the aperture 28, a slit or cut 29 of irregular form is provided which extends from the aperture 28 into the body of the member but falls short of the edge of the member.

In actual practice, this stop has been found to be exceedingly effective for the purpose for which it is designed. It is a device which may be economically manufactured, being formed in a cutting machine 115 and, when in use, effectually blocks the cement or concrete from flowing beyond the bulkhead, which, as shown in Fig. 7, would otherwise occur.

What we claim is:

1. An instrumentality for utilization in concrete construction including a relatively thin sheet member provided with a rod-receiving aperture and a slit extending from the edge of the member to the aperture.

2. An instrumentality for utilization in concrete bulkhead construction including a relatively thin sheet member provided with a central rod-receiving aperture and with a slit which extends from one edge of the

member to the aperture and permits the insertion of a rod in the aperture.

3. An instrumentality for utilization in concrete bulkhead construction including a relatively thin sheet member provided with a rod-receiving aperture and with a slit which extends from one edge of the member to the aperture; the member being flexible to permit the sections of it adjacent the slit to be shifted relatively for permitting the insertion of a rod in the aperture.

4. An instrumentality for utilization in concrete bulkhead construction including a flexible member provided with a rod-receiving aperture and with a slit which extends from one edge of the member to the aperture, there being a plurality of slits extending from the edge of the aperture but falling short of the edge of the member.

20 5. As an article of manufacture, a stop for concrete bulkhead construction comprising a member provided with a weakening line adjacent one edge thereof and having a central aperture, a slit extending from one edge of the member to the aperture, a floor-engaging section bendable at the weakening line and angularly to the plane of the main portion of the stop, and a slit radiating from the aperture but not extending to the edge of the member.

6. As an article of manufacture, a concrete stop for bulkhead construction, relatively thin in cross-section, flexible, and comprising a member including a body-portion and a bendable portion adjacent one edge thereof, the body-portion being provided with a central rod-encompassing aperture, and a series of slits radiating from the aperture, one of the slits extending to the edge of the member.

7. A bulkhead structure comprising an upstanding bulkhead provided with a series of notches and a cement-stop for each of the notches comprising a relatively thin sheet member of larger dimensions than its proximate notch and having a rod-receiving aperture, and an angular slit extending from an edge of the member to the aperture.

8. A bulkhead structure comprising an upstanding bulkhead provided with a series of notches and a cement-stop for each of the notches comprising a relatively thin sheet member of larger dimensions than its proximate notch and having a rod-receiving aperture, an angular slit extending from an edge of the member to the aperture and positionable over the notch.

9. A bulkhead structure comprising an upstanding bulkhead provided with a series of notches and a cement-stop for each of the notches comprising a relatively thin sheet member of larger dimensions than its proximate notch and having a rod-receiving aperture, an angular slit extending from an edge of the member to the aperture, po-

sitionable over the notch, and relatively thin.

10. A bulkhead structure comprising an upstanding bulkhead provided with a series of notches and a cement-stop for each of the notches comprising a member of larger dimensions than its proximate notch and having a rod-receiving aperture and provided with a weakening line adjacent one edge thereof, an angular slit extending from an edge of the member to the aperture, positionable over the notch, relatively thin, and having a floor-engaging portion at one side of the weakening line to permit the engaging-portion to be angulated to the body-portion of the stop.

11. A bulkhead structure comprising a support or floor, a bulkhead upstanding therefrom and provided at its lower edge with a series of notches, reinforcing rods, bars or wires extending through said notches, and a cement stop overlying each notch and of greater dimensions than the notch and having a central aperture through which one of the rods extends and a slit extending from an edge of the stop to the aperture whereby the positioning of the rod in the aperture is facilitated.

12. A bulkhead structure comprising a support or floor, a bulkhead upstanding therefrom and provided at its lower edge with a series of notches, reinforcing rods extending through said notches, and a cement stop overlying each notch and of greater dimensions than the notch and having a central aperture through which one of the rods extends and a slit extending from an edge of the stop to the aperture whereby the positioning of the rod in the aperture is facilitated, and a brace therefor.

13. A bulkhead structure comprising a support or floor, a bulkhead upstanding therefrom and provided at its lower edge with a series of notches, reinforcing rods extending through said notches, and a cement stop overlying each notch and of greater dimensions than the notch and having a central aperture through which one of the rods extends and a slit extending from an edge of the stop to the aperture whereby the positioning of the rod in the aperture is facilitated, and braces therefor sustained by the support.

14. A bulkhead structure comprising a support or floor, a bulkhead upstanding therefrom and, provided at its lower edge with a series of notches, reinforcing rods extending through said notches, and a cement stop overlying each notch and of greater dimensions than the notch and having a central aperture through which one of the wires extends and a slit extending from an edge of the stop to the aperture whereby the positioning of the rod in the aperture is facilitated, and braces therefor

sustained by the support; and the stop being provided with a weakening line adjacent one edge and thereat bent to provide a floor-engaging section.

15. A bulkhead structure including a cement-supporting floor, an elongated bulkhead upstanding therefrom and provided at its lower edge with a series of incuts or notches, a series of reinforcing rods positioned above the floor and extending through the notches, and a series of cement stops juxtaposed to one face of the bulkhead, each covering its proximate notch and being of dimensions somewhat greater than those of the notch and having a central aperture through which a rod extends, the wire being encompassed by the walls of the stop, the

latter having a slit extending from the aperture to an edge of the stop.

16. An instrumentality for utilization in concrete-bulkhead construction including a relatively thin sheet-member provided adjacent its central portion with a series of radiating slits and having an elongated slit extending from one edge of the member to approximately its said central portion.

In testimony whereof we affix our signatures in presence of two witnesses.
